ATTORNEY.

UNITED STATES PATENT OFFICE.

EDWARD BRANDT AND HILIA J. BARTON, OF DETROIT, MICHIGAN.

DESIGN FOR A WALL PLATE FOR LIGHTING FIXTURES.

Application filed October 21, 1925. Serial No. 15,216. Term of patent 7 years.

To all whom it may concern:

Be it known that we, EDWARD BRANDT and HILIA J. BARTON, citizens of the United States, residing at Detroit, in the county of Wayne and State of Michigan, have invented a new, original, and ornamental Design for a Wall Plate for Lighting Fixtures, of which the following is a specification, reference being had to the accompanying drawings, forming part thereof.

Fig. 1 is a front elevation of a wall plate for lighting fixtures embodying our invention.

Fig. 2 is a side elevation thereof.

Fig. 3 is a plan view thereof.

We claim:

The ornamental design for a wall plate for lighting fixtures as shown.

HILIA J. BARTON.
EDWARD BRANDT.
